CANDLE SNUFFER

Joseph Soss, Roselle, N. J.

Application September 22, 1932
Serial No. 634,283

8 Claims. (Cl. 67—24)

This invention relates to devices for use in snuffing or extinguishing candles used in churches, in the home or in other places; and the object of the invention is to provide a device 5 of this class which will eliminate the spilling of the melted wax or paraffin of the candle in the operation of snuffing or extinguishing the same; a further object being to provide an attachment for snuffer casings which is readily attachable 10 and detachable with respect thereto and includes means for catching any drip of wax which may run down the sides of the attachment; a further object being to provide an attachment which is so mounted in connection with the snuffer cas- 15 ing and of such structure as to provide an air passage between the attachment and the casing with openings at the top and bottom of the at- tachment preventing the building up of a pres- sure in the upper end of the attachment in the 20 operation of snuffing a candle; a still further object being to provide an attachment of the class described which forms a liner for the snuffer casing with means for retaining the liner against displacement therefrom, said liner being prefer- 25 ably composed of a flame retarding or fire proof substance, and the major part of which is spaced from the wall of the snuffer casing to insulate the same to prevent heating of said casing; and with these and other objects in view, the inven- 30 tion consists in a device of the class and for the purpose specified, which is simple in con- struction, efficient in use, and which is con- structed as hereinafter described and claimed.

The invention is fully disclosed in the follow- 35 ing specification, of which the accompanying drawing forms a part, in which the separate parts of my improvement are designated by suitable reference characters in each of the views, and in which:

40 Fig. 1 is a side view of a snuffer made according to my invention.

Fig. 2 is a sectional detail view of part of the construction shown in Fig. 1, on an enlarged scale.

45 Fig. 3 is a section on the line 3—3 of Fig. 2; and,

Fig. 4 is a view similar to Fig. 2, and showing a modification.

For the purpose of illustrating one use of my 50 invention, I have shown in Fig. 1 of the drawing one form of snuffer device which I employ, the device consisting of a relatively long shank portion 10 terminating at one end in a handle portion or hand grip 11 of any desired design or contour, and at the other end in a curved

and outwardly directed extension 12, with which the snuffer 13 is coupled. At one side of the shank 10 adjacent the curved end 12 thereof is a tube 14, in which is supported a taper or lighting strand 15 which projects through the upper and outwardly curved end 14a of the tube as clearly seen. This taper may be extended as consumed by a plunger 16 operated by a finger piece 17 which passes through and operates in an elongated slot 18 formed in the wall of the tube 14 between the keepers or retaining collars 19 employed for attaching the tube to the shank 10.

The snuffer casing 13 is conical in form and terminates at its large open end in an attach- 70 ing flange 20, with which a retaining ring 21 is detachably coupled through bayonet joints 22 or in any other manner. The ring 21 projects beyond the end of the casing 13 and terminates in an inwardly and upwardly curved rim 23 which 75 forms means for retaining a liner or attachment 24 within the casing 13. The attachment 24 is also conical in form and may be made of any suitable material, it being preferred that a non- inflammable material be used, for example, this 80 liner may be constructed of asbestos or an asbestos composition which may be molded or otherwise formed into the desired shape.

In the construction shown the outer wall of the attachment has circumferentially spaced 85 outward projections or lugs 25 which are adapted to seat in the bore of the casing 13 to space the wall of the attachment 24 therefrom to provide a chamber 26. The top of the attachment is provided with an opening 27 to place the in- 90 terior of the attachment in communication with the chamber 26 at the top of the casing, it being understood that the top of the attachment is spaced from the top of the casing as shown in Fig. 2 of the drawing.

In Fig. 2, the attachment 24 is also provided adjacent the lower end thereof with apertures 28 which place the interior of the attachment in communication with the chamber 26 so that in the operation of placing the snuffer over a lighted candle, no air pressure can be built up at the top of the candle within the attachment by reason of the fact that the chamber above the candle is in communication with atmosphere through the openings 27, the chamber 26 and 105 the apertures 28. However, it is not essential that the apertures 28 be employed, and in this case, the wall of the casing 13 may be apertured as seen at 13a in Fig. 4 of the drawing. With 110 this type of construction, it will be understood

that it is not absolutely essential to provide the chamber 26 throughout the length of the attachment, the only advantage in this instance being that the provision of this chamber will tend to 5 keep the wall of the casing 13 cool in excessive use of the snuffer.

The bottom of the attachment 24 terminates in an inwardly curved wall 29 which engages the rim 23 as clearly seen in Fig. 2 to support the 10 attachment 24 against displacement from the casing, and further provides a trough in which molten wax which may run down the wall of the attachment may be collected. In addition to the advantages herein specified, it will be understood 15 that by constructing a snuffer in accordance with my invention, the liner or attachment may be readily attached and detached at will for replacement of a new liner or attachment, in which event the necessity of cleaning 20 out or removing wax from the casing and/or ring 21 is eliminated.

These attachments may be produced and sold at a nominal cost and replaced as often as desired or practical. At the same time, my attachment will preserve and lengthen the life of the snuffer casing and will not interfere with or destroy any plating finish on the inner or outer surfaces thereof, thus maintaining the same in preserved state at all times.

It will be understood that while I have shown one type of attachment and one method of arranging and mounting the same in the snuffer casing, my invention is not limited in this respect, nor am I necessarily limited to the particular type of snuffer casing and manner of supporting the attachment therein as herein disclosed, nor is my invention limited to the means herein disclosed for supporting or handling the snuffer casing, and various other 40 changes in and modifications of the construction herein disclosed may be made within the scope of the appended claims without departing from the spirit of my invention or sacrificing its advantages.

Having fully described my invention, what I claim as new and desire to secure by Letters Patent, is:

1. A device of the class described comprising a conical casing, the wide end of which is open, said 50 casing being adapted to be placed on a lighted candle in the operation of extinguishing the same, and means in said casing for exposing the chamber thereof above the candle to atmosphere to eliminate air pressure above the candle.

2. A device of the class described comprising a conical casing, the wide end of which is open, said 60 casing being adapted to be placed on a lighted candle in the operation of extinguishing the same, means in said casing for exposing the chamber thereof above the candle to atmosphere to eliminate air pressure above the candle, said means comprising a liner arranged in the casing and in spaced relation to the contracted end thereof to form a chamber, the upper end of the liner having an opening communicating with said chamber.

3. A device of the class described comprising a 70 conical casing, the wide end of which is open, said casing being adapted to be placed on a light-

ed candle in the operation of extinguishing the same, means in said casing for exposing the chamber thereof above the candle to atmosphere to eliminate air pressure above the candle, said means comprising a liner arranged in the casing and in spaced relation to the contracted end thereof to form a chamber, the upper end of the liner having an opening communicating with said chamber, and means for retaining the liner against displacement from the casing.

4. A device of the class described comprising a conical casing, the wide end of which is open, said 80 casing being adapted to be placed on a lighted candle in the operation of extinguishing the same, means in said casing for exposing the chamber thereof above the candle to atmosphere to eliminate air pressure above the candle, said means comprising a liner arranged in the casing and in spaced relation to the contracted end thereof to form a chamber, the upper end of the liner having an opening communicating with said chamber, means for retaining the liner against displacement from the casing, and means for spacing the side walls of the liner from the casing to provide an air chamber therebetween to eliminate direct heat flow to the casing wall.

5. A device of the class described comprising a conical casing, the wide end of which is open, said 90 casing being adapted to be placed on a lighted candle in the operation of extinguishing the same, means in said casing for exposing the chamber thereof above the candle to atmosphere to eliminate air pressure above the candle, said means comprising a liner arranged in the casing and in spaced relation to the contracted end thereof to form a chamber, the upper end of the liner having an opening communicating with said chamber, means for retaining the liner against displacement from the casing, and means for spacing the side walls of the liner from the casing to provide an air chamber therebetween to eliminate direct heat flow to the casing wall.

6. In devices of the class described employing 100 a conical casing, a liner attachment consisting of a conical body of flame repellent material, the contracted end of said body having an opening, and the open end of said liner body terminating in an inwardly extending rim.

7. In devices of the class described employing 110 a conical casing, a liner attachment consisting of a conical body of flame repellent material, the contracted end of said body having an opening, the open end of said liner body terminating in an inwardly extending rim, and the outer wall of said body including circumferentially spaced projecting members.

8. A snuffer device of the class described comprising a hollow conical body, the flared end of which is open and adapted to receive a lighted candle in the operation of extinguishing the same, and the upper contracted end of said body having an opening arranged above the candle placed in said body to maintain in the chamber above the candle placed therein substantially atmospheric pressure.

JOSEPH SOSS.
